UNITED STATES PATENT OFFICE.

WILLIAM G. LEWI, OF ALBANY, NEW YORK, ASSIGNOR OF ONE-FOURTH
TO EDWARD F. HACKETT, OF ALBANY, NEW YORK.

MATCH-BOX HOLDER.

SPECIFICATION forming part of Letters Patent No. 792,335, dated June 13, 1905.

Application filed October 22, 1904. Serial No. 229,621.

To all whom it may concern:

Be it known that I, WILLIAM G. LEWI, a citizen of the United States, residing in Albany, county of Albany, State of New York, have 5 invented certain new and useful Improvements in Match-Box Holders; and I do hereby declare the following to be a full, clear, and exact description of the invention, such as will enable others skilled in the art to which it app- 10 pertains to make and use the same.

This invention relates to holders for match-boxes of the familiar sliding tray and cover variety.

My improved holder is designed to support 15 the box in such manner that the sliding tray will be partly open in order that matches may be taken therefrom and ignited on the chemically-prepared or other abradent surface commonly applied to one or more of the 20 sides of the box-cover.

In the accompanying drawings, Figure 1 represents a vertical section taken through a match-box contained within a holder, showing one form or modification of my invention, 25 said holder being shown as attached to a suitable wall or other support. Fig. 2 represents a perspective view of the holder shown in Fig. 1. Fig. 3 represents in vertical section the upper end of one of my holders and 30 a modified form of attaching device. Fig. 4 represents a transverse section of Fig. 3. Fig. 5 represents an elevation of the end of the holder shown in Fig. 3. Fig. 6 represents a vertical section showing the holder engaging 35 the narrow sides of a match-box. Fig. 7 represents a vertical section of a match-box and modified form of holder, showing other attaching means therefor.

The several forms of holder illustrated are 40 more particularly designed to hold the well-known paper or veneer slide-boxes commonly used to contain "safety-matches" and comprising an open-top tray A and an open-ended tubular casing or cover B, adapted to in- 45 close the top, sides, and bottom of the tray.

The holder in its several modifications is formed from a blank of sheet metal, preferably of general rectangular form, and comprises a main portion 1, a tray - supporting

shelf 2, a channel 3, and a front guard or keeper 4. The shelf 2 is formed by approximately right-angled bends 5 and 6 and the channel by a return-bend 7 of the blank to leave sufficient space or interval between the walls of said channel to receive the top or 55 side of the cover B. In forming the channel 3 the blank is preferably bent to such an extent that the keeper 4 will incline inwardly somewhat toward the body 1, as shown in Fig. 2, thereby exercising a corresponding spring 60 clamping action on the box to hold it in place. I contemplate this same clamping action in all of the modifications. In the modified form shown in Fig. 7 the metal of the blank is again bent upon itself at 8 (thereby 65 reinforcing the front guard or keeper) and thence rearward at 9 and downward at 10 to bring the lower end 11 of the holder in the same plane with the body 1 thereof.

In use the body 1 of the holder is introduced 70 between the cover B and the bottom a of the tray A of the match-box, the box being pressed down until an end wall a' of the tray rests upon the shelf 2 of the holder. Further downward pressure on the cover B 75 of the box will force its lower front edge to the bottom of the channel 3. The upper portion of the end wall of the tray may now be torn off, as indicated, to expose the contents of the box. 80

The holder carrying the match-box may be secured in any usual way to a wall C or other support--as, for instance, by engaging the upper end of the body 1 with a nail projecting from the wall C; but to avoid the side swing 85 or deflection of the holder and box due to the force used in striking a match on one or the other of the abrasive side edges of the box I have provided means to maintain the holder in position as against lateral movement. Thus 90 in Figs. 1, 2, 3, 5, and 6 I have shown the body 1 of the holder as provided at its upper end with an elongated slot 12 to engage a fastening device, as 13, (hereinafter termed an "anchor,") consisting of an elongated body 95 from one edge of which project two spikes 14 and 15, adapted to be driven into the wall or support C, the other edge being provided op-

posite the spike 14 with a headed stud 16. The upper end of the anchor is cut away toward the rear to leave a shoulder 17, the height of this shoulder, the length of the slot 12, and 5 the head of stud 16 bearing such a relation to each other that the holder may be removed from or restored to the anchor only by a movement at right angles to the body of the holder, thereby providing an efficient safeguard 10 against accidental detachment of the holder from its support. To remove the holder when the parts are in the position shown in Fig. 1, it must be first moved upward to clear the upper end of the slot 12 from the shoulder 17, 15 then moved horizontally away from the support C, and finally it must be given a slight downward movement to clear the lower end of the slot from the head of the stud 16.

In Figs. 3 and 4 I have shown another form 20 of anchor designed to prevent the unauthorized removal of the holder from the wall or the box from the holder. It consists of a threaded post 18, projecting from the outer edge of the anchor-body, a yoke or saddle 19, 25 mounted on said post and straddling the body of the anchor, its edges resting on the holder, and a nut 20 to clamp the parts together securely. As shown, the anchor-body is enlarged at a point in alinement with the spike 30 14, the threaded post 20 forming a continuation of such enlargement. With this form of anchor I prefer to use a holder having a slot shaped as in Fig. 5—that is to say, with opposite recesses 12^a intermediate of its ends to 35 accommodate the enlargement of the anchor. It is obvious that upon clamping the saddle A down upon the holder by means of the nut 20 it cannot be removed except by a person having a tool to fit the nut.

40 The form of holder shown in Fig. 6 is substantially identical with that of Fig. 1 except as to width and is designed for use in positions where the support C is too narrow to permit the box of matches to be placed flatwise against it. As shown, the holder is adapted to engage the narrow side edges of the box, and as the abradent surface of such boxes is usually applied to the side edges the keeper 4 is shortened to expose a corresponding portion of the outer side edge of the box 45 and is bent back upon itself to reinforce it.

In Fig. 7 the upper and lower extremities of the holder are each provided with a perforation 21 22, the latter to receive a headed nail 23, which secures the lower end of the holder permanently to the support C, a headless stud 24 being fixed in said support at a point to engage the perforation 21, as shown. So arranged, it will be seen that the holder 55 and its box are secure against lateral movement.

To remove an empty box from the holder, the upper end is sprung outwardly free from

the stud 24 and turned to one side on the nail 23 as a pivot until the box can pass the 65 stud 24. The box may then be removed and replaced by a fresh box, whereupon the parts are again restored to the position shown in Fig. 7.

In some instances, as indicated in dotted 70 lines in Fig. 2 of the drawings, I may provide a front guard or keeper 4 with a cut-away portion, so as to correspondingly uncover the front panel of the box for the purpose of permitting the front portion of the box to be 75 used as an abrading-surface or the surface to which the chemical igniting composition may be applied. By so doing the act of striking the match on the box would not exert a lateral strain on the box, and therefore the holder 80 would not require a special anchoring device to obviate the lateral movement.

Having thus described my invention, what I claim is—

1. A match-box holder, comprising a main 85 body portion constituting the rear wall of the holder, a shelf projecting therefrom, and a channel or receiving-pocket depending from the front edge of the shelf, the front panel of the pocket constituting the front wall of the 90 holder.

2. A match-box holder, comprising a main body portion constituting the rear wall of the holder, a shelf projecting therefrom, and a channel or receiving-pocket depending from 95 the front edge of the shelf, the front panel of the pocket constituting the front wall of the holder and being inclined rearwardly to exert a spring clamping action on the box.

3. A match-box holder, comprising a main 100 body portion constituting the rear wall of the holder, a shelf projecting therefrom, and a channel or receiving-pocket depending from the front edge of the shelf, the front panel of the pocket constituting the front wall of the 105 holder and being provided with a return reinforcing-bend.

4. A match-box holder, having a main body portion provided at top with an elongated slot, an elongated anchor detachably engaging the 110 slot of the holder, and means to lock the holder upon the anchor; substantially as described.

5. A match-box holder, having a main body portion provided at top with an elongated slot, an elongated anchor detachably engaging the 115 slot of the holder, a threaded post projecting from the anchor, a saddle straddling the anchor and engaging the holder, and a nut adapted to the threaded post; substantially as described.

In testimony whereof I affix my signature in 120 presence of two witnesses.

WILLIAM G. LEWI.
